CARBON DIOXIDE REFRIGERATING APPARATUS

Clara E. Quinn, St. Petersburg, Fla., assignor to
Frank S. Reed, St. Petersburg, Fla.

Application February 26, 1946, Serial No. 650,217

9 Claims. (Cl. 62—91.5)

1

This invention relates to improvements in refrigerating apparatus of the type employing a solid refrigerant as the source of refrigeration, as for example solid carbon dioxide.

A broad object of this invention is to provide an improved system for utilizing solid carbon dioxide as the source of refrigeration for railway cars, trucks and the like.

An object of the invention is to provide a system for more efficiently effecting the transfer of heat from the space to be refrigerated to the solid carbon dioxide bunker for absorption thereby.

An object of this invention is to provide a system of this type employing a liquid circulatory secondary refrigerant moving between the point of heat absorption from the space to be refrigerated to the point of transfer of heat to the refrigerant.

Another object of the invention is to provide two or more double walled heat conducting bunkers for the solid carbon dioxide interconnected with the cooling plates or coils in such a manner that the secondary refrigerant will have a maximum contact time with the heat exchange wall through which it gives up its absorbed heat to the refrigerant.

A more specific object of the invention is to provide a double walled container construction of this type of such form as to permit of the use of metal walls of minimum thickness while attaining maximum strength.

Other and more detailed objects of the invention will be apparent from the following description of the embodiment thereof illustrated in the attached drawings.

This invention resides substantially in the combination, construction, arrangement and relative location of parts, all as will be described in detail below.

In the accompanying drawings.

Figure 1 is a top plan view of the apparatus of this invention showing the insulating housing in cross-section; and

Figure 2 is a cross-sectional view taken on the line 2—2 of Figure 1.

The insulating housing which may be a refrigerating cabinet, the wall of a railway car, or the wall of a truck, for example, is shown in part in the figures as comprising an end wall 10, side walls 11, a partition 12, and a roof 13 made of any suitable heat insulating material and forming a closed cabinet or space for the solid carbon dioxide bunkers. The partition 12 has been omitted from Figure 2 but its position is

2

apparent from Figure 1. The solid carbon dioxide bunkers comprise the double wall vessels 14 and 15 and 16 and 17 forming the closed chambers B and A respectively. These bunkers can be made of any suitable heat conducting material, preferably metal, and are shown as having an oval form in cross-section to provide maximum strength. They can, for example, be made elliptical or spherical in form to provide other suitable vessel shapes. As a result of these forms the metal walls may be made of a minimum thickness to withstand the mechanical loading and gas fluid pressures to which they will normally be subjected, to facilitate rapid heat transfer therethrough.

As is clear from Figure 1, each of the vessels 14 to 17 inclusive is closed at all sides to form hermetically sealed containers and the inner containers can be supported within the outer containers by any suitable form of spacing means, not shown. Extending between suitable openings in the roof 13 and the cabinet are hatches 18, 19, 22 and 24 having removable closures 20, 21, 23 and 25. The hatches extend through the outer vessels 15 and 17 at sealed joints and open into the inner vessels 14 and 16, forming therewith overall sealed connections. For example, these hatches may be made of metal and be welded in place in the double wall containers. It will be seen from Figure 1 that a hatch is provided for each end of each bunker to facilitate proper filling of each bunker formed by the inner containers 14 and 16 with solid carbon dioxide which is diagrammatically illustrated in Figure 2 by the reference character D1.

The spaces defined by the inner containers 14 and 16 are interconnected by pressure equalizing carbon dioxide gas conduit 26, see Figure 2. Supported above the bunkers in any suitable manner, as for example in a recess in the roof of the cabinet, is a container 27 having a filling connection and removable cap 28 accessible from the top of the container. A branch pipe 29 connects the container 27 with the chambers A and B.

Extending along each side of the cabinet are thin, plate-like cooling members 31 which may be thin, plate-like hollow, hermetically sealed containers of metal. If desired a series of cooling coils or other forms of heat exchangers can be used.

Referring to Figure 2, the upper end of one cooling member 31 is connected by a conduit 32 with the chamber A at one end and the lower end of the member 31 is connected by means

of the conduit 30 with the chamber B. Similarly, at the other end, as is clear from Figure 2, the other cooling member will be connected at its upper side to the chamber B by means of conduit 36, and at its lower side to the space A by means of the conduit 35. As shown in Figure 1, conduits 32 and 36 are provided with valves 33 and 37 respectively, which are thermostatically controlled by means of the temperature sensitive bulbs 34 and 38 respectively. These bulbs are 10 exposed to the space to be cooled so that the temperature therein will influence the setting of the valves to control the flow of circulating cooling fluid.

The circulating system comprising the chambers A and B, conduits 30, 32, 35 and 36, and cooling members 31 will form closed circulatory systems for the liquid secondary refrigerant which will completely fill the systems up to a level in the expansion tank 27. The amount of liquid in the system will not be sufficient to fill the expansion tank 27 so that while insuring that the system will be full at all times, provision is made for any change in volume of the liquid that may occur as the result of temperature changes. Additional liquid can be added as required through the filling connection by removing cap 28.

The operation of this system will be apparent, but it may be briefly reviewed. As the liquid in the cooling members 31 absorbs heat it rises and travels back to the chambers A and B through the conduits 32 and 36. It is discharged into these spaces at the top where it may move in heat exchange relation with inner walls 14 and 16 to give up its heat to the solid carbon dioxide. The fluid entering the chamber A from the conduit 32 is ultimately delivered back to the opposite member through the delivery conduit 35 so that it must travel throughout the length of the chamber A before it is returned to the cooling member. This insures an efficient extraction of heat therefrom by the associated solid carbon dioxide. In a similar way the fluid return from the other cooling member 31 is returned to the left hand end, Figure 1, of chamber B, and is delivered from the right hand end of this chamber to the supply conduit 30 and thence to the opposite member. Thus it will be seen that any unit of the liquid will alternately circulate through both members and must travel along the walls 14 and 16 throughout their length at the time of heat discharge to the refrigerant.

The rate of flow of the cooling liquid which is moved under thermosiphonic action will be further controlled by means of the valves 33 and 37 which in turn will be opened and closed in response to temperature changes in the space being refrigerated.

Those skilled in the art will appreciate that the secondary refrigerating liquid may be any one of a number of materials known and used for this purpose. Generally speaking, they should be liquids having large heat absorbing capacity which will not freeze under the conditions normally encountered in the operation of the system, and which will preferably, but not necessarily, remain in liquid state under these conditions.

It is equally clear that it is not necessary to use solid carbon dioxide as the refrigerant, but it is preferred for this system. The conduit 26 will serve to equalize gas pressure conditions within the bunkers themselves, that is within the spaces defined by the walls 14 and 16. No gas escape conduit is shown since it is assumed that the necessary leakage can take place around the

closures for the hatches, but suitable members can be provided which may or may not include pressure responsive valves if desired.

From the above description it will be apparent to those skilled in the art that the subject matter of this invention is capable of some variation, and I do not, therefore, desire to be limited to the illustrative example given herein, but rather by the claims granted me.

What is claimed is:

1. In a refrigerating apparatus the combination including a heat insulated cabinet forming an apparatus and a storage compartment, a pair of elongated double-walled heat conducting vessels in said apparatus compartment, a pair of heat exchange members in said storage compartment, a return conduit from one of said members to one end of the space defined by the walls of one of said vessels and a supply conduit from said member to the corresponding end of the space defined by the walls of the other vessel, a return conduit from the second member to the latter space at its opposite end, and a supply conduit connecting said second member with the former space at its other end, whereby a series liquid secondary refrigerant circuit is formed by the spaces of the double-wall vessels, the coils and conduits.

2. In a refrigerating apparatus as disclosed, 30 a heat insulating cabinet forming an apparatus and a storage compartment, a pair of elongated double-walled heat conducting vessels in said apparatus compartment, the inner space of each forming a solid refrigerant bunker, a pair of heat exchange members in said storage compartment and connections between said members and the spaces formed by the walls of said vessels to cause a circulatory liquid secondary refrigerant to flow alternately through both refrigerating members and in so doing to travel throughout the length of the spaces defined by said double-walled vessels.

3. A refrigerating apparatus including a heat insulated cabinet forming an apparatus compartment and a storage compartment, a pair of double-walled heat conducting vessels in said apparatus compartment each forming a closed space, the chamber defined by the inner wall of each vessel providing a bunker for a solid refrigerant, a liquid circulatory system comprising a pair of hollow heat exchange plates disposed in said storage compartment, a supply connection and a return connection for each of said plates, said supply connections communicating respectively with said spaces at the opposite ends of said spaces and said return connections communicating respectively with said spaces at their other ends to form with said spaces closed circulatory systems, and a heat exchange liquid filling said systems whereby the liquid moving through said plates absorbs heat from the storage space and gives up that heat to the solid refrigerant in said bunkers while traveling lengthwise of said spaces.

4. In the combination of claim 3, hatches having removable closures through which a solid refrigerant may be introduced into said bunkers.

5. In the combination of claim 3, an expansion tank for said liquid communicating with both of said spaces.

6. In the combination of claim 3, a conduit establishing communication between said bunkers.

7. In a refrigerating apparatus the combination including a heat insulated cabinet divided

into an apparatus compartment and a storage compartment, a pair of double-walled heat conducting vessels in said apparatus compartment each forming a closed space and extending throughout the width of said apparatus compartment, a pair of hollow heat exchange members lying along the sides of said storage compartment, a pair of conduits connecting one of said members with the adjacent ends of said spaces, a pair of conduits connecting the other member 10 with said spaces at the other ends of said spaces; said hollow members, the conduits connected thereto and said spaces forming a closed circulatory system adapted to contain a liquid secondary refrigerant, and a conduit establishing communication between the innermost vessel of said pair of double-walled vessels.

8. In the combination of claim 7, a thermostatically controlled valve in one conduit of each

pair to control the rate of flow of liquid secondary refrigerant in said circulatory systems.

9. In the combination of claim 7, a thermostatically controlled valve in one conduit of each 5 pair to control the rate of flow of liquid secondary refrigerant in said circulatory systems, and hatches having removable closures through which a solid refrigerant can be introduced into the innermost vessel of each pair of double-walled vessels.
